Des. 178,510

Patented Aug. 14, 1956

178,510

TOY ROBOT FIGURE

Robert W. Fink, Nevada, Iowa

Application April 11, 1955, Serial No. 35,459

Term of patent 14 years

(Cl. D34—4)

Fig. 1

Fig. 2

Fig. 3

Fig. 1 is a top plan view of a toy robot figure, embodying my new design;

Fig. 2 is a front elevational view thereof;

Fig. 3 is a side elevational view thereof.

The back of the figure is substantially plain.

I claim:

The ornamental design for a toy robot figure, as shown and described.
